Inventor:
John Germanotta
By: W. F. Kellogg May.

UNITED STATES PATENT OFFICE

2,375,643

TOILETRY APPLIANCE

John Germanotta, Milwaukee, Wis.

Application April 12, 1944, Serial No. 530,690

8 Claims. (Cl. 311—17)

This invention relates to improvements in toiletry appliances, having for an object to provide a device particularly advantageous for use by professional beauticians, hairdressers, etc., so constructed and designed as to provide a universally adaptable, convenient and most practical means, in immediate proximity to the head of a person being worked upon by the artisan, upon which preparations, implements and appurtenances, normally used and being used during such work, may be received and satisfactorily supported thereon; hence, materially facilitating the carrying out of the work and eliminating that loss of time usually incurred under those working conditions where the operator is required to place his equipment and materials upon tables or other articles of furniture, and to carry the same to and fro, as between the person and said furniture.

Moreover, it is an object of the invention to provide a device of the stated character capable of being firmly supported upon the body of a person being worked upon without annoyance, inconvenience or discomfort to or of such person, and when desired, may be quickly and safely removed.

Another object of the invention is to provide a toiletry accessory receiving and supporting tray which, generally, will be self-adjusting to that particular portion of a person's body receiving the same, and too, may have the supporting means provided thereto, further adjusted in certain unusual instances of usage whereby to insure its position in an approximately horizontal plane; consequently, assuring the secure retention of matters and devices placed thereupon against accidental or undesired displacement.

The invention furthermore aims to provide a device that, by reason of its placement upon or with relation to a person being worked upon by a user of the same, will localize the incident labor, and hence, effect a minimizing of effort and time expenditure.

The foregoing, as well as other objects, advantages and meritorious teachings of the invention, will be in part obvious and in part pointed out in the following detailed disclosure thereof, when taken in conjunction with the accompanying drawing, it being understood that the particular form of the invention presented herein is a precise and, what is now considered to be, the best mode of embodying its principles, but that modifications and changes may be made in specific embodiments, without departing from its essential features.

In the drawing:

Figure 1 is a top view of my improved device

showing the arrangement and formation of the tray feet, the rearward hinged leg and the adjustable check.

Figure 2 is a side elevation of the same in operative position upon a person, the latter being shown in dotted lines, and

Figure 3 is a transverse section, taken on the line 3—3 of Figure 1, looking in the direction in which the arrows point.

Having more particular reference to the drawing, in connection with which like characters of reference will designate corresponding parts throughout, the improved device may be stated to comprise a yoke-shaped or substantially U-shaped tray body 1, constructed of suitable material, as for example, composition matters, metal, plastics, wood, etc. The normally upper side of the tray body is dished throughout its area, as indicated at 2, thus providing substantially upstanding bordering walls entirely thereabout. The inner side or portion of the tray body may be and preferably is so shaped as to substantially conform to the curvature of the back and sides of a person's neck, whereby to effect its comparatively snug and embracing engagement thereabout when in operative position, as is hereinafter more fully described.

To support the tray body 1 in a substantially horizontal plane upon the shoulders of a person and in embracing engagement about her neck, the free end portions of the opposite legs or branches of the tray body are provided with feet 3, appropriately secured to the under-sides of such body. The feet are of complementary construction or formation and size, having rearwardly inclined normally rearward sides 4, and their normally rearward and inner side portions curved upon themselves to eliminate the presence of any and all corners or sharp angles which, when engaged with adjacent portions of the person's body, might cause some discomfort. Moreover, because of the described inclined and curved formation of the referred to portions of said feet, it will be understood and appreciated that said portions will be more or less self-adapting to those parts of a person's body adjacent to or engaged by the same. The normally rearward or basal portion of the tray body 1 has a substantially transversely disposed hinge mounting block or like element 5 fixed to its corresponding under-side portion, which block, in turn, has a supporting leg 6 strap-hinged thereto, as at 7. It will be noted, in this connection, that the upper portion of the thus hingedly mounted leg 6 has bearing engagement upon the adjacent and substantially flat side of the mounting block 5, and therefore, that under

certain conditions of usage or positioning, will be retained in a position at substantially right angles to the adjacent part of the tray body 1. The length of this supporting leg 6, as will be seen, upon reference to the accompanying drawing, is greater than the depth of the several feet 3, in that the feet 3 will normally rest upon adjacent portions of a person's chest and the leg 6 will have supporting engagement, at a lower point, with a portion of such person's back. This is more or less necessary to insure the supporting of the tray body 1 in a substantially horizontal plane with respect to the head of the referred to person.

In some instances, because of different physical characteristics of people, it may become necessary to adjust the positioning of the hinged supporting leg 6, i. e., said leg to have proper supporting engagement with a part of the person's back, may need be swung slightly inwardly, and when in such inwardly swung position, must be locked or blocked against outward swinging movement from the back. To effect such adjustment and securing of the hinged leg 6 in the referred to adjusted position, whereby to insure its proper functioning for retaining the tray body 1 in the above-mentioned substantially horizontal plane, I provide a wedge-like lock or check 8 adapted to enter between the flattened rearward side of the mounting block 5 and the adjacent upper portion of the leg 6. Obviously, the extent of longitudinal engagement or introduction of said wedge-like check 8 between the mounting block 5 and said portion of the supporting leg 6 will vary the outward limitation of hinged or pivotal movement of said leg 6 with respect to the tray body 1, and hence, will assure the effectual retention of the lower portion of the hinged leg 6 in engagement with an adjacent part of a person's back. To mount the wedge-like check 8 in slidable and operative position with respect to the mounting block 5 and leg 6, I may and preferably do provide the normally outer end of such check with a shank 9 slidably received in a bracket or fitting 10 fixedly mounted upon an appropriately adjacent portion of the under-side of the tray body 1 and provided with a laterally extending handle or finger piece 11 whereby sliding motion, to the desired extent or degree, may be imparted to the check, for those reasons above indicated.

The dished normally upper surface of the tray body 1 may, of course, have its bottom either curved or flat, such as conditions or preference may dictate. Also, said tray body is formed with receptacle receiving openings 12 in proximity to the free end portions of its opposite branches or legs. These openings flushly communicate with pockets or wells, of appropriate depths formed in each of the aforesaid supporting feet 3. The openings 12 formed in the free end portions of the tray body 1 may be surrounded by shouldered portions 13 in order to provide suitable blocks or baffles to prevent the unwanted or undesired dropping of various accessories received upon the tray body 1 into openings 12 and the wells of the several feet 3, i. e., when the same are not receiving receptacles or cups, such as indicated by the numeral 14.

In usage of my improved toiletry appliance, the yoke-like tray body 2 is forwardly engaged with or about the neck of a person so that such person's neck is, more or less, snugly received within the loop-like inner portion of the tray body. The tray body is supported in a substantially horizontal position about said person's neck

by reason of the fact that the now forwardly disposed feet 3 thereof will have self-adapting or self-adjusting engagement with the adjacent portions of the person's chest. With the tray so positioned, the hingedly mounted leg 6 is now so positioned with respect to the tray body 1 as to have its free end firmly though comfortably engaged with an adjacent portion of such person's back. At this point, the wedge-like check 8 is so adjusted with respect to the mounting block 5 of the adjacent portion of the leg 6 as to limit its outward swinging movement with respect to the tray body 1, in the manner hereinabove described. With the tray thus engaged or mounted upon or from the shoulders of the person, it will be observed that the inclined normally rearward portions 4 of the feet 3 and the leg 6 will function to securely though comfortably clamp or lock the tray body in a satisfactory operative position and against undesirable shifting movement with respect to such person's body during and throughout the period of usage thereof. To disengage or remove the appliance from a person's shoulders, it need only be lifted slightly and then rearwardly moved, in a substantially horizontal position, so as to become disengaged from its previous embracing relationship with respect to the person's neck.

Various devices, implements, materials or accessories, obviously, can and will be received and supported upon the tray body 1 during that period of its usage when supported upon a person in the manner above described. A most convenient usage of the improved device will be found in those instances where a beautician is engaged in the dyeing of a person's hair, in that dye holding containers 14 (one or more) may be received within the openings 12 and the wells of the adjacent feet 3. When thus positioned, said containers will be most conveniently located with relation to the person's hair, and additionally, will be positively prevented from accidentally overturning.

The device will be also especially advantageous for usage in the dressing of a person's hair, during which time the operator may place his implements, hair pins, etc., upon the dished portion of the tray body 1, rather than being required to walk to and fro as between the person and articles of furniture normally used to receive or support such devices, materials or accessories.

It is, as will be readily understood, quite desirable that the tray body 2 and its feet 3 be constructed of rugged though light material. Various composition matters will serve or suit such constructional requirements.

I claim:

1. A device of the character described, comprising a yoke-like tray, body engaging supports on the normally under sides of the opposite extremities of said tray, and movable supporting means on another portion of the tray spaced from the first mentioned supports co-operable with the body engaging supports.

2. A device of the character described, comprising a yoke-like tray, feet having curved body engaging portions connected to the normally under-sides and forward extremities of said tray, and adjustable supporting means on said normally under-side of the tray adjacent the normally rearward portion thereof.

3. A device of the character described, comprising a neck embracing tray having its normally forward side open, feet connected to the normally under-side of said tray adjacent its

forward extremities having their free portions shaped to be body conforming, and adjustable supporting means on the normally under-side of the tray adjacent its rearward portion and spaced from said feet.

4. A device of the character described, comprising a substantially U-shaped tray, feet fixedly connected to the normally under-side and normally forward extremities of said tray, the exposed portions of said feet being shaped to have substantially flush bearing contact with the adjacent portions of a person's body, and adjustable supporting means on the normally under-side of said tray adjacent its normally rearward portion.

5. A device of the character described, comprising a substantially U-shaped tray, feet carried upon the normally under-side of said tray in proximity to the free extremities of its opposite sides, each of said feet having curved extremities and obliquely disposed inner side contiguous with said curved extremities of the same, and adjustable supporting means carried on the normally under-side of said tray adjacent its basal portion.

6. A device of the character described, comprising a yoke-like tray, body engaging supports on portions of said tray, movable supporting means on another portion of the tray spaced from

the first mentioned supports, the normally upper side of said tray having openings therein communicating with openings in each of said body engaging supports, and portions surrounding said tray openings extending above the normally upper side of said tray.

5 7. A device of the character described, comprising a substantially U-shaped tray, feet carried by the normally under-side of said tray in 10 proximity to the outer extremities of its opposite sides, the ends of each said feet being curved and the normally inner sides of said feet being obliquely disposed and contiguous with the curved ends of the same, and a supporting leg hingedly 15 connected to the normally under-side of said tray adjacent its basal portion and intermediately of said feet.

8. A device of the character described, comprising substantially U-shaped tray, feet having 20 curved extremities and obliquely formed inner sides, carried by the normally under-side of the tray in proximity to the free ends of the opposite sides thereof, a leg hingedly connected to the normally under-side of said tray adjacent its 25 basal portion and intermediately of said feet, and means engageable with the hinged portion of said leg for limiting the extent of its swinging movement with respect to the tray.

JOHN GERMANOTTA.
